OF SLIDE FASTENER ELEMENTS ON SLIDE
FASTENER BANDS

Albert Süsskind, Lugano, Switzerland

Application January 19, 1940, Serial No. 314,630
In Switzerland January 11, 1939

4 Claims. (Cl. 153—1)

The object of the invention is a machine for attaching Zipper hooks to their band.

An important purpose of the invention is to secure, by very simple and rugged means, an accurate and reliable attaching without skewing, buckling or indenting said hooks.

A further purpose of the invention consists in indexing or step by step feeding of the band with exclusion of joints, springs or lever actions and, therefore, in a very accurate and reliable manner.

Further features, objects and advantages of the invention will become apparent from the following specification in connection with the accompanying drawings in which the new machine is shown by way of example.

In the drawings

Fig. 1 is a part elevation of the attaching station of the machine on an enlarged scale, some parts being shown in section, the attaching slide being shown raised far enough to seat a hook upon the bead of the band before the attaching operation proper;

Fig. 2 a section on the line 2—2 of Fig. 1, some parts being omitted for the sake of clearness;

Fig. 3 an elevation similar to Fig. 1 with the slide in a position corresponding to the end of the attaching operation;

Fig. 4 a schematic elevation of a modification of the attaching device;

Fig. 5 a schematic elevation of a further modification of the attaching device;

Fig. 6 a partial section, on a smaller scale, on the line 6—6 of Fig. 3, the slide being shown in a lowered position during its return stroke, some parts being omitted;

Fig. 7 a schematic side elevation on a smaller scale, of part of Fig. 1;

Fig. 8 a schematic plan view of a modification of the bracing device for the bead of the band;

Fig. 9 a schematic side elevation of part of a supply channel guide or fall channel guide provided with a tip-over section for changing the position of the hooks relative to the sense of the movement thereof;

Fig. 10 an elevation, similar to Fig. 9, of a modification;

Fig. 11 an elevation of the device shown in Fig. 10 with another relative position of the parts;

Fig. 12 a schematic side elevation of the slide and of the lower part of the supply channel of a further modification.

The main operative part of the machine is an attachment slide 1 reciprocable in the sense of the arrow 2. A bridge 3 is guided by pins 4 in holes 5 of the slide.

The slide 1 has a slot 6 for the passage of the band or tape 7 to which the hook or fastener element 8 is to be attached.

The band 7 is provided with a bead 10 which is supported or braced on each side of the band

by the teeth 11 of a toothed wheel 12 rigidly secured to an idler shaft 13.

On pivots 14 of the slide 1 and in semicircular sockets 15 thereof are mounted two sector-shaped attachment jaws 16 swingable in a slot 17 (Fig. 2) between the front plate 18 and the rear plate 19 of the slide 1.

The jaws 16, in the position of the slide 1 shown in Fig. 1, and in all lower positions form 10 with their operative surfaces 20 a V-shaped receiver exactly conformed to the outer edge surfaces 21 of the legs or arms 22 of the still undeformed hook 8 to be attached to the bead 10. In Figs. 1 and 3 some small clearance is shown, 15 only for clearness of illustration, between the surfaces 20 and 21, in fact, however, during all the fastening operation proper, they are in contact with each other, as indicated in Fig. 2, substantially throughout the length of the surfaces 21.

The inner parts of the plates 18 and 19 of the slide 1, in the form of flanges 23 and 24, snugly overlap the front and back surfaces, i. e. the broadsides, of the legs or arms 22 of the hook 8. The flanges 23 are continued at 240 along the main part of the hook 8 so that the latter throughout its length, and particularly throughout the length of the legs 22, is held well confined between closely fitting overlapping rigid parts during the attaching operation proper. This is particularly important in the beginning of the attaching deformation when the tendency to buckling and skewing of the hooks is the greatest.

When the slide 1 is in a position (not shown) 35 lower than the position of Fig. 1, a hook or fastener element 8 is introduced into the wide slot 66 (Figs. 1-3) of the front plate 18 so that said element lies on the back plate 19 immediately in front of the flanges 240, not yet centered exactly between them. If the slide is not inclined sufficiently to the horizontal to allow the element to slide down automatically between the flanges 240 said element is carried along frictionally by and travels with the slide towards the bead 10, until the element reaches said bead and is arrested thereby. The slide, however, continues its movement whereby the element, if not slid down already before as explained, comes into the narrower part of the V-shaped receiver and is progressively overlapped by the flanges 23, 240 and is automatically centered until the position of Fig. 1 is reached.

Then, by the pressure of the advancing pins 4 against the surfaces 25 of the jaws 16, the latter 55 are pressed against the faces 21 of the legs 22 of the element which thereby is now centered definitely upon the bead 10 and is pressed thereagainst with progressively increasing pressure until the legs 22 yield and are bent around the bead 10, as shown in Fig. 3 in which said legs

are shown in their final position 22'. In this operation the legs 22 enter into the gaps 26 (Fig. 6) between the teeth 11 of the wheels 12.

Rigidly secured to or integral with the back plate 19 of the slide 1 are two cams 27 which, when the slide, during its return stroke, is lowered beyond the position shown in Fig. 1, strike against the upper part, i. e. the ends of the legs 22, of the last attached hook 8, as shown in Fig. 6, and thereby advance the band 1, immovable transversally, with the hooks 8 already attached thereto, by one step in the direction of the arrow 28. During this movement the hooks 8 on the bead 10 act as a toothed rack turning the idler wheel 12 one step. The downward stroke of the slide brings the wide slot 66 of the front plate 18 in line with the attached hooks for free passage of the last attached hook.

Fig. 7 shows diagrammatically the relative positions of the parts and, besides, shows an additional solid support 29 for the band at one side only.

In the modification shown in Fig. 4 the slide 30 and flange 31 substantially correspond to the slide 1 and flanges 240 of Fig. 1. Levers 32 pivoted at 33 to the slide 30 correspond to the jaws 16 and have flanges 34 overlapping the hook 8 tightly from both sides on the front and back surfaces. The links 340 form with the levers 32 a toggle-like structure and are pivoted at 35 to a reciprocating driving member 36.

The effect of the modified structure is substantially like that of Fig. 1.

In the modification shown in Fig. 5 the slide 37 with its flanges 38 again corresponds to the slide 1 and flanges 23 of Fig. 1. Surfaces 39 of the slide 37 again form a V-shaped receiver for the hook 8. The attaching pressure is exerted here by a pair of rollers 40 mounted in the slide 37.

The modification shown in plan view in Fig. 8 differs from the device of Fig. 7 only by using, for bracing the bead 10, two crown wheels 41 instead of the ordinary gear wheels 12.

In Fig. 9 the inclined slide 42 corresponds to the slide 1.

The hooks 8 from any source of supply fall down through the channel guide or chute 43 with their legs 22 directed forwardly, i. e. downwardly. They have to be presented, however, to the slide 42 with their legs facing toward the band or rearwardly. Hence between the upper part 43 of the chute and its delivery part 44 is inserted an arched tip-over part 45 in which the hooks, after reaching the closed end of the part 43, fall through tilted intermediate positions 8' to the reversed final position 8" in which they are delivered to the slide 42.

In the modification shown in Figs. 10 and 11 the tip-over channel guide 45 supplies the hooks directly to the slide 42. If the lowermost hook 8 does not tip over automatically it is tipped over positively when an arm 46 secured to the slide 42, upon leftward-downward movement of the slide from the position of the Fig. 10 to the charging position of Fig. 11, pushes the locking pin 47 into the channel guide 43. This pin 47, in a known manner, supports the upper hooks in the channel guide 43 at the time of charging the lowermost hook into the slide.

In the modification shown in Fig. 12 the supply

channel guide 48 and slide 49 correspond to the parts 44 and 42 of Fig. 9. The outlet 50 of the channel guide 48 is usually blocked by a tooth 51 pressed into the channel by a leaf spring 52.

When the slide 49 moves to the right a wedge 53 attached thereto acts upon the lower i. e. left end of the spring 52 and lifts the tooth 51 out of the channel 48 thereby allowing the lowermost fastener element in the channel to fall into the outlet 50 and upon the top surface 54 of the slide 48. When the slide returns to the left its receiver 55 comes beneath said element which, then, is pushed into said receiver by the tooth 51 under the pressure of the spring 52 released now by the cam 53.

I claim:

1. A machine for attaching Zipper hooks to their band by bending the arms of said hooks around a bead of said band, said machine comprising, in combination, means for bracing said bead from the side of the band opposite to the side to which the hook is to be attached, a slide, a V-shaped receiver connected with said slide and conformed to and adapted to receive and support an open hook with its arms pointing to said side, members of said receiver, adapted, in the beginning of said bending, to snugly overlap both broad sides of said arms over substantially the full length of said arms, said members at least on one of these broad sides consisting of converging flanges, means for delivering a hook, broadside ahead, into a first position in front of but free of overlapping by said flanges, and means for moving said slide to overlap said arms by said flanges, and to seat said hook upon said bead by pressure exerted directly upon the arms of said hook, and to bend said arms around said bead by continuance of said pressure.

2. A machine as claimed in claim 1 in which the slide movable parallel to the plane of said band is provided with flanges for supporting, in said receiver, the open hook to be attached, said flanges of said slide adapted to overlap said hook while in said receiver, two pressure jaws pivoted to said slide and conformed with their insides to the outsides of the legs of said hook, and a pusher adapted to exert upon said jaws a force parallel to the plane of said band to first develop, by the pressure exerted by said jaws directly upon said legs, an adequate seating pressure, and then swing said jaws toward said band again by that same pressure.

3. A machine as claimed in claim 1 in which a slide movable parallel to the plane of said band is provided for supporting in said receiver the open hook to be attached, two pressure jaws pivoted to said slide and conformed with their insides to the outside of the legs of said hook, and a pair of links forming with said jaws a toggle-like structure and pivoted to a driving member movable parallel to the plane of said band.

4. A machine as claimed in claim 1 in which a slide is provided for supporting, in said receiver, the open hook to be attached, said slide adapted to be moved parallel to the plane of said band, two rounded pressure members like rollers being mounted on said slide and being adapted, upon movement of said slide, first to put said hook firmly astride said band, and then to close the legs of said hook upon said band.

ALBERT SÜSSKIND.
